UNITED STATES PATENT OFFICE.

CHARLES L. DAVIS, OF CHICAGO, ILLINOIS, ASSIGNOR, BY DIRECT AND MESNE ASSIGNMENTS, OF ONE - HALF TO AUGUST HEUER, JR., CHARLES A. BROWN, GEORGE L. CRAGG, AND A. MILLER BELFIELD, OF CHICAGO, ILLINOIS.

PNEUMATIC MOTOR.

SPECIFICATION forming part of Letters Patent No. 692,194, dated January 28, 1902.

Application filed December 17, 1900. Serial No. 40,141. (No model.)

To all whom it may concern:

Be it known that I, CHARLES L. DAVIS, a citizen of the United States, residing at Chicago, in the county of Cook and State of Illinois, have invented a certain new and useful Improvement in Pneumatic Motors, (Case No. 6,) of which the following is a full, clear, concise, and exact description, reference being had to the accompanying drawings, forming 10 a part of this specification.

My invention relates to motors adapted for operation by pneumatic pressure and in particular to a variety thereof adapted for operation by a suction or exhaust wind-current.

15 The principal object of the invention is to provide a simple, practical, and efficient motor of the kind specified.

In the accompanying drawings, Figure 1 is a rear elevation of a portion of a pneumatic 20 motor embodying my invention. Fig. 2 is an end elevation of the same with the valve mechanism shown in vertical section.

In the motor which I have shown in the drawings there are three collapsible bellows 25 A A A, which are arranged in alinement with one another with their collapsible ends uppermost. The rear walls $a a a$ of the bellows A A A are made rigid or stationary, being desirably secured rigidly to the frame B.

30 In the rear of the three bellows A A A is a horizontally-disposed rotary shaft 1, which is the driving-shaft of the motor. This shaft 1 is provided with three crank portions 2 2 2, and these crank portions 2 2 2 carry links 3 3 3, which are connected with the rear movable walls $a' a' a'$ of the bellows A A A. The 35 crank portions 2 2 2 of the shaft 1 are desirably set one hundred and twenty degrees apart from one another. It will be seen that

40 by this arrangement the bellows A A A when they collapse will in turn act upon the driving-shaft 1 through the medium of the crank portions 2 2 2 thereof and the links 3 3 3, and this action of the bellows will occur at each 45 third of a revolution of the driving-shaft 1, so that there will be a continuous propulsion of that shaft and at the same time there will be no dead-center.

The number of bellows A A A is not par-

ticularly material to my invention, it being 50 merely desirable to have a plurality thereof, preferably three, so as to have a substantially continuous action and also to avoid a dead-center.

Each of the bellows A A A is provided with 55 valve mechanism by which the air can be alternately admitted to and exhausted from its interior. One of these valve mechanisms is well shown in section in Fig. 2. Referring to this figure, an exhaust-passage 4 is understood to lead to and communicate with an exhaust-chest leading to any suitable or desired form of wind-inducing apparatus, by which a condition of exhaust is continually maintained in the exhaust-passage 4. This 60 exhaust-passage 4 has a port 5, and this port 5 opens into a connecting-passage 6, which serves to connect the exhaust-passage 4 with a passage 7, communicating with the interior of the bellows A. The passage 6 is provided 65 with an air-port 8, which communicates with the outside air. The exhaust-port 5 is controlled by a valve 9, conveniently in the form of a flat slide-valve, which works upon a suitable valve-seat 10. The air-port 8 is controlled by a valve 11, also conveniently in the 70 form of a simple flat slide-valve, which works upon a seat 12, conveniently provided by the outside of the wall 13 of the valve-chest. The valves 9 and 11 are connected with one another so as to move in unison—as, for example, by a projection 14, secured to the valve 11 and engaging a projection 15 of the valve 9—the arrangement being such that the valve 9 will completely close the port 5 at 75 a time when the valve 11 begins to open the air-port 8 and will begin to open the port 5 at a time when the valve 11 completely closes the air-port 8. The valve 11 is connected with the rotary driving-shaft 1 by a link 16 and a crank 80 portion 17 on the rotary shaft, it being understood, of course, that the valves 11 11 for the other bellows are also connected with the rotary shaft 1 by similar links 16 and crank portions 17 17. The cranks 17 17 17 are on the 85 same side of the rotary driving-shaft 1 as the crank-shafts 2 2 2 for the links 3 3 3 of their respective bellows A A A and are at the same

angle with the shaft as the said cranks 2 2— that is to say, the valve-crank 17 for the bellows A shown in the drawings is on the same side of the shaft 1 as the crank 2 for that bellows, and the crank 17 is set at the same angle with the shaft as the crank 2 and similarly with the other sets of cranks for the other bellows, the bellows and valve-cranks for each of the three bellows being thus set together 10 and at one hundred and twenty degrees from the cranks of the other bellows. The valve 11 is so connected with the rotary shaft 1 that the valve is in the position shown in the drawings—that is to say, at the point where it either 15 opens or closes the air-port 8 when its crank is midway between the opposite ends of its throw, as shown in the drawings. In this way the maximum extent of movement of the valves 9 and 12 is secured for a given extent 20 of rotation on the part of their cranks at a time when the air-ports of these valves are being opened and closed. As a matter of preferred arrangement the air-ports 8 8 are made very wide, as shown by reference to 25 Fig. 1.

The connection 14 by which the valves 9 and 11 are connected with one another is attached to a flat strip 18, which is secured to the outer face of the valve 11 by screws 19 19. The strip 30 18 is provided with slots 20 20, as shown in Fig. 1, which permit its adjustment relatively to the valve 11. In this way the valve 9 can be properly adjusted relatively to the valve 11.

The operation of the device, of course, is 35 that when the wind-inducing apparatus is operated so as to cause a suction or exhaust condition in the passages 4 4 4 of the three bellows A A A the bellows A which at the time is in communication with its passage 4 will 40 collapse, thereby causing a rotation of the driving-shaft 1. This will start the motor, and having thus become started the rotation of the driving-shaft 1 will operate the other valve mechanisms properly, so that each in 45 turn will open its bellows A first to the exhaust and then to the air, with the result that the three bellows will successively act upon the driving-shaft 1, and thereby cause a continual and even rotation thereof. By so connecting the valve mechanism of each bellows 50 with its operating-crank of the driving-shaft the creation of the exhaust condition in each pneumatic or bellows and the subsequent admission of air thereto occur in the most rapid 55 possible manner. This effect, so far as the air is concerned, is augmented by the great width on the part of the air-port 8. As a result of this arrangement the action of each bellows is exceedingly quick and powerful, so 60 that the action of the motor as a whole is very effective and economical.

What I claim as my invention is—

1. In a pneumatic motor, the combination 65 with a bellows, of a passage communicating therewith, an exhaust-passage, a passage connecting the bellows-passage and exhaust-passage and communicating with the latter by

way of a port formed at the end thereof, the said connecting-passage having an air-port, and valve mechanism controlling the port of the 70 exhaust-passage and the air-port of the connecting-passage, substantially as set forth.

2. The combination with a collapsible bellows, of a passage communicating therewith, an exhaust-passage, a passage connecting the 75 bellows-passage with the exhaust-passage and communicating with the latter by way of a port formed at the end thereof, the said connecting-passage having an air-port, a valve 80 controlling the exhaust-port, a second valve controlling the air-port, a connection between 85 said valves whereby the exhaust-valve opens the exhaust-port at a time when the air-valve closes the air-port and vice versa, and mechanism for operating one of said valves by the collapse of the bellows, substantially as 90 set forth.

3. The combination with the bellows, of valve mechanism for controlling the admission of air to the bellows and the exhaust of 95 the same therefrom, and a crank for operating said valve mechanism, the said crank being connected with the valve mechanism so as to begin the admission and exhaust of air at a time when the crank is midway between 100 the ends of its throw.

4. The combination with the bellows, of a rotary driving-shaft having bellows and valve-crank, portions arranged on the same side of the shaft and at the same angle therewith, a link connected with the movable member 105 of the bellows and also connected with the crank therefor on said shaft, a passage leading to the interior of the bellows and having air and exhaust ports, a pair of valves, one controlling the exhaust-port and one controlling the air-port, the said valves being connected together so as to move in unison and being arranged so that the exhaust-valve 110 opens the exhaust-port when the air-valve closes the air-port and vice versa, and a link connected with said valves and with the crank therefor on the rotary shaft, the connection being such that the valves open and close their respective ports at a time when the 115 crank therefor is substantially midway between the ends of its throw, substantially as set forth.

5. The combination with the bellows and a rotary driving-shaft having a bellows and 120 valve-cranks, of a link extending between the movable member of the bellows and the crank therefor on said shaft, a passage communicating with the interior of the bellows and having air and exhaust ports, a pair of 125 slide-valves adapted to control the air and exhaust ports of said bellows-passage, said valves being connected together so as to move in unison, and being arranged so that the exhaust-valve closes the exhaust-port at a time 130 when the air-valve opens the air-port and vice versa, and a link extending between one of said valves and the crank therefor on said shaft, substantially as described.

6. The combination with the bellows, of the passage 7 communicating therewith, an exhaust-passage 4, a passage 6 connecting the passage 7 with the passage 4, the latter being provided with a port 5 opening into the passage 6 and the passage 6 being provided with an air-port 8, a slide-valve 9 arranged to travel upon a seat 10 for controlling the port 5, an air-valve 11 controlling the air-port 8, a connection 14 attached to the air-valve 11 and engaging the exhaust-valve 9, a rotary shaft connected for operation with the bellows, the said shaft having a crank 17, and a link 16 extending between the crank 17 and the air-valve 11, substantially as described.

7. In a pneumatic apparatus, a structure providing passages 4 and 7 and a connecting-passage 6, the latter having a port 8 and communicating with the passage 4 by way of the port 5, a valve 9 adapted to control the port 5, a valve 11 arranged to control the port 8, and means for connecting the valves 9 and 11, substantially as described.

8. A motor comprising a plurality of bellows, a rotary shaft having bellows-cranks corresponding to the bellows, the said cranks being arranged at different angles to the shaft, and the shaft also having valve-cranks which are arranged at the same angles with the shaft as the bellows-cranks, links connecting the movable members of the bellows with said bellows-cranks, valve-chests, one for each bellows, each valve-chest having a passage communicating with the interior of the bellows and provided with air and exhaust ports, valve mechanism for controlling said ports, and connections between the valve mechanisms and the respective cranks, said connections being each adapted to cause the valves to open and close their respective ports at a time when the cranks therefor are midway between the ends of their throws, substantially as described.

9. A motor comprising a plurality of bellows, a rotary shaft having cranks corresponding to the bellows, the said cranks being arranged at different angles to the shaft and

the shaft also having cranks for valves arranged at the same angles with the shaft as 50 their respective bellows-cranks, links connecting the movable members of the bellows with the cranks therefor, valve-chests, one for each bellows, each valve-chest having a passage communicating with the interior of 55 the bellows and provided with air and exhaust ports, valve mechanism for controlling said ports, each of said valve mechanisms comprising a slide-valve 9 for the exhaust-port, a slide-valve 11 for the air-port, and a 60 connection 14 between said valves and links between the valves 11 and their respective cranks, substantially as described.

10. The combination with the slide-valves 9 and 11, of a strip 18 having a sliding connection with the valve 11, and a piece 14 secured to the strip 18 and engaging the valve 9, substantially as described.

11. In a pneumatic motor, the combination with a bellows, of a single passage communicating therewith and having air and exhaust ports and a valve mechanism for simultaneously controlling both of said ports, as set forth.

12. In a pneumatic motor, the combination 75 with a bellows, of a passage communicating therewith and having both air and exhaust ports, a double-valve mechanism comprising a couple of valves for simultaneously controlling both of said ports, and means for actuating said double-valve mechanism, as set forth.

13. In a pneumatic motor, the combination with a bellows, of a passage communicating therewith and having both air and exhaust 85 ports, a double-valve mechanism comprising a couple of valves for controlling said ports, and means for reciprocating said valves substantially in unison, substantially as described.

In witness whereof I hereunto subscribe my 90 name this 8th day of December, A. D. 1900.
